UNITED STATES PATENT OFFICE.

MOSE D. EAST, OF SEATTLE, WASHINGTON.

GARAGE.

Application filed September 2, 1924. Serial No. 735,341.

To all whom it may concern:

Be it known that I, MOSE D. EAST, a citizen of the Dominion of Canada, and resident of the city of Seattle, in the county of King and State of Washington, have invented certain new and useful Improvements in Garages, of which the following is a specification.

My invention has for its chief object the provision of a structure which is accessible throughout to automobiles, and in which all available ground space will be economically used for storage, either of goods or automobiles.

In modern cities the problem of providing sufficient space for storage of goods handled by automobile trucks, for storage of automobiles themselves, and for terminal facilities for persons traveling in automobile stages, in accessible locations, has become a serious one. Convenient locations for such purposes are always in districts where ground space is at a premium, and where if available at all it is very expensive. It is therefore essential to obtain the maximum of available space, for terminal purposes, for storage, or for parking cars, upon the minimum ground space. It is a most important object of my invention to provide such a structure which will increase the available floor space for each story to more than the ground floor area of the lot on which the structure is built.

A further important object is the provision of a system of ramps or runways which will facilitate communication between all parts of the structure and which will facilitate the control and flow of traffic through the building, to the end of avoiding confusion and of moving the maximum number of cars in the minimum of time.

A further object is the provision of such a structure and ramps for communication therein, wherein the ramps and the necessary passageways require the minimum of space so that all possible space is conserved for storage of cars.

Other objects, and especially objects which have particular reference to details of construction and arrangement may be ascertained from a study of the drawings, wherein my invention is shown in its present preferred forms, and of the following speci-

fication and the claims terminating the same, which define the scope of my invention.

Figure 1 is an isometric view of such a structure, parts of the walls being broken away to illustrate the interior arrangement thereof.

Figure 2 is a typical floor plan of a double unit type of garage.

Figure 3 is a vertical section through such a building as is illustrated in Figure 2, a part being broken back to show a section approximately on the line 3—3 of Figure 2.

Figure 4 is an enlarged vertical section on line 4—4 of Figure 2.

Figure 5 is a section similar to Figure 3, showing a single unit of my structure intended for erection upon a smaller lot.

In modern cities it is essential that structures be provided for storing cars off the streets and in such a way that they are available at all times without confusion and without serious delay. Attempts have been made to provide such storage garages, but a given lot, according to plans used heretofore, will accommodate only such multiples of the lot area as there may be stories. Further, it has been found impracticable to provide garages having more than two or three stories of height, for the reason that elevator carriage of automobiles from street to upper stories is slow, inconvenient, and expensive, and therefore impractical, and for the further reason that no system of ramps has heretofore been devised which would afford easy communication from street to any of the upper stories and which would at the same time provide for as many cars as might desire to move in or out at the same time, without confusion and without enormous wastage of storage space. Heretofore a single ramp has generally been provided to accommodate both upward and downward traffic, that is, cars going into and out of the garage.

Such storage structures require good ventilation, hence high ceilings, and the ramps heretofore employed to communicate between stories have been long because of the ceiling height, and wide because of the necessity of accommodating two oppositely bound streams of traffic. Generally such ramps are built against the walls for support, the ramp from a story below leading

in at one side wall and the ramp to the story above leading out at the adjacent side wall. The storage space necessary to make the garage a profitable investment is thus 5 seriously reduced, because two sides of each floor are largely given up to ramps.

By my invention the storage space equivalent to a building on a 210 foot lot, for example, can be secured upon a lot having a 10 width of only 160 feet, without loss of proper clearance and ventilation, with an increase of convenience and safety in the handling of cars, and with a considerable decrease in the floor space necessary for passageways, thus in all ways increasing the storage space and at the same time making every car immediately accessible and easily removable from the building and easily placed in its stall.

20 These results are accomplished by overlapping the stories, that is to say, by dividing each story into sections, and placing these sectional or half stories at levels which will permit one half story to overlap the 25 story next thereabove or therebelow, thus to provide storage space therebetween, yet without essentially reducing the clearance necessary for proper ventilation and light.

This can best be illustrated by reference 30 to the accompanying drawings. Figure 1 of these drawings is an isometric view of a storage garage which may be taken as a single unit, and which is also illustrated in vertical section in Figure 5. The structure

35 proper consists of surrounding walls, the wall 1 being designated the front wall for convenience, and the wall 10 the rear wall, the front wall or a side wall 12 having one or more entrances 11 at the ground level G.

40 Extending from the front wall 1 toward the rear wall 10, but terminating short thereof, are the several stories 2, above the ground floor 20. As stated above, these stories 2 do not extend entirely through the building

45 from the front to the rear wall, but terminate short of the rear wall. Extending forward from the rear wall, however, toward the front wall, but as in the case of the stories 2 terminating short of the front wall, are half-stories 3. The inner edges 21 of the stories 2 lie within the inner edges 31 of the stories 3, that is to say, the stories overlap to an extent sufficient to provide storage space between the overlapping portions of the stories.

50 Thus in effect each story 2 and half-story 3 together form one complete floor, and are spaced above the one next thereabove or next therebelow the height of a half story, and in the overlapping space thus provided two

55 cars can be stored instead of one, so that the space gained in this way is the space occupied by one car, multiplied by the number of spaces possible throughout the length of the building, that is between the side walls

60 65 12.

It is necessary, of course, to communicate between the several stories and half stories, and for this purpose ramps are provided, generally arranged in pairs and preferably lying not adjacent the side walls of the 70 building, but inwardly therefrom. Preferably, also, two complete series of ramps are employed and each series will lead a car from the ground floor upward to any upper story, or downward therefrom, without the necessity of using ramps of the other series, so that two entrances may be employed, thus avoiding congestion at any one entrance, yet without increasing undesirably the space allotted to ramps. Further, I place the ramps 75 in the overlapping portion of the floors, at an edge of each story or half-story, where the space they take up is less than if they were positioned outwardly of the edges of the floor sections. From a given line of departure on any floor, inward of its inner edge 21 or 31, the ramps of a pair lead upward to the next floor and downward to the floor below.

80 As shown, a ramp 40 affords communication between the ground floor 20, having an entrance 11, and the lowermost half-story 3. A companion ramp 4, forming the other ramp of the pair and placed adjacent the ramp 40, leads upward from the story 3 to the 85 first or lowermost of the stories 2. The ramp 4, however, is not intended for use of a car which reaches the story 3 from the companion ramp 40, but rather it is intended for 90 cars descending from the lowermost story 2 to the half-story 3. Cars ascending to the half-story 3 by means of a ramp 40, instead of using the companion ramp 4 for ascending further to the story 2, pass along a passageway 41 (as shown by the arrow B) to the 95 next pair of ramps, where it may ascend to the story 2 by means of a ramp 4', situated there. Cars descending from the story 2 to the half-story 3 use the ramp 4 and then 100 move along a passageway 41, as shown by the arrow B', to the ramp 40' which is the companion ramp of the ramp 4', and by this descend to a lower floor 20. Movement on the floor 2 in ascending or descending takes 105 place in the direction of the arrows A and A', ascending and descending, respectively, moving along the aisle 42 provided on these stories. It will be seen thus that all movement, whether ascending or descending, is in 110 a counterclockwise direction, in the present arrangement, and that there is, in fact, room in the aisle 42 for simultaneous movement of two columns of cars side by side, one column ascending and the other descending, and that these columns never cross nor become 115 confused.

120 In the double form, which is my preferred form, instead of moving along the aisle 41 on the stories 3, movement preferably occurs along the cross aisle 43, as shown by the 125 130

arrows C and C', ascending and descending, respectively. Thus a car entering at 11 on the ground floor, rises along a ramp 40 to the first half-story 3, crosses this half-story 5 along the aisle 43 in the direction of the arrow C, rises to the first story 2, that is, to the section in the end of the building opposite its entrance 11, along a second ramp 4, then in the direction of the arrow A along 10 the aisle 42 on the story 2, then up the ramp 4' at the opposite end of the aisle 42 to the second half-story 3, thence following the arrow C along the cross aisle 42 and up the next ramp 4' to the second story 2, (actually 15 to the third floor of the building), that is to the section of the second full story which is in the same end of the building. The car may then continue in the direction of the arrow A, climbing up to the upper 20 stories in the same direction and along the same series of ramps. It will be seen, however, that at any time it may move along the aisles 41, 42 or 43 to a stall on any particular floor. Preferably, on the half-stories 25 3 of the double-unit building, movement is not along the lines of the arrows B and B', but instead, after rising along a ramp 40 the cars will pass through the cross aisle 43 and thence in the direction of the arrows D and 30 D' to reach any particular stall on this story 3, or to move to the front section of the first or lowermost of the stories 2. In this manner movement in a counter-clockwise direction is always maintained and there is never 35 any traffic in a reverse direction, that is to say, cars never meet within the garage.

Along the outside walls are provided a series of stalls 50 where cars may be stored. These stalls may be defined by posts 6 so 40 positioned as to include a given number of cars between them, and of course serving to support the upper stories and roof. By proper designing these posts may be positioned just far enough from the outside 45 walls 1 to permit a car to be moved back of the line of posts; thus these posts 6 together with the next series of posts 61 define the aisles 42. On the half stories 3 of the double-unit building, as shown in Figures 2 and 50 3, cars may be parked end to end in the center of the story, that is, at one side of each aisle 41, or long busses may be parked here, using the length of two stalls, as indicated at X in Figure 3. Posts 62 may define 55 these stalls 51 and aisles 41, and also define the cross aisles 43.

On each of the stories and half stories the space at the inner edge is used for parking. Between the inner edge 31 of the half story 60 3, for example, and the aisle 41, there is sufficient space to park a car, and this space is overlapped by the inner edge 21 of the story 2 next thereabove. Inasmuch as the stories 2 should be spaced 15 feet or more 65 for proper ventilation, light, and overhead

clearance, this leaves a space of 7 feet 6 inches, less only the thickness of the floor, between the level of the story 2 and its half-story 3. This space is sufficient for the height of most modern cars and I have 70 therefore provided stalls 5 in this space. This space lies between the row of columns 61 and the edge 31 or 21 of the story, as the case may be. For the stories 2 the columns 61 define the outer edge of the stalls 5, the 75 inner edge being defined by the companion columns 61 extending upward from the half story 3 below, and by a cross beam 63 secured to the columns 61 and lying above the floor space. These beams 63 project sufficiently from the wall 22 to form a curb against which the rear wheels of an automobile may strike. For the half-stories 3 the stalls 5 are defined by the columns 61 and the wall 32 extending upward from the 80 edge 31, or the beam 63 lying inward thereof.

It will be clear, especially from inspection of Figure 4, for example, that this arrangement provides stalls 5 on each story and half 90 story which are overlapped, that is to say, cars on the story 2 in the space 5 lie immediately above the cars on the corresponding half-story 3. There is thus secured double the amount of space along this overlapping 95 portion of the stories and half-stories as would ordinarily be provided in garages not employing overlapping stories.

This overlap is also of importance as permitting the employment of short ramps instead of the very long ramps required to reach the length of a 15 foot or 16 foot story height, and these ramps may be steeper because of their shortness. They may, moreover, be supported inward of the outer walls 100 of the building, thus leaving these walls free for storage space and windows. It will be noted that notwithstanding that the difference in level between each story and its corresponding half story is only approximately 110 7 feet 6 inches, the clearance along the ramps is approximately 15 feet, inasmuch as each ascending ramp 40 lies immediately above a corresponding ascending ramp 40 for the next story above, whereas in the ordinary type of building the ramps lie along the outside walls and for each story there is lost the space along one wall to accommodate the ascending ramp and the space along the other wall for the ramp leading to the 115 story next above.

Another advantage of the overlapped section is shown in Figure 4. The stalls 5, if desired, may be used as private locking stalls and the cars locked in place by the owner, 125 as, for example, by means of a metal curtain 55 which may be drawn down from above to enclose the stall 5. The height of this curtain need only be sufficient to reach from the floor of the stall 5 to the half story 130

next thereabove, instead of reaching the entire height of the ceiling of any given story.

A building constructed according to this design provides storage space for the maximum number of cars on any given size lot.

In effect it increases the floor area for each story by at least the amount of floor provided in the overlapping portion thereof. In addition it provides for free and continuous circulation of cars, whatever their overhead clearance, throughout the building, either ascending or descending, and permits handling of such cars by drivers of only ordinary ability, without confusion and in

the shortest period of time. It increases lighting and ventilation within the building, the ceilings being high, and all outside walls being clear for windows. It utilizes storage space most economically and uses but a very

small amount of the total floor area for internal communication, that is to say, for ramps and aisles. It provides private stalls at low cost if these are desired, and in a word, produces a building which is best adapted for its purpose and which most economically uses the ground area available.

Such a building may also be employed for terminal purposes or for storage. When used for terminal purposes it permits access of a large number of cars to the building at any given time and permits these cars to enter and leave without interference. When used for storage of goods it permits goods of large size and light weight, requiring large space for storage, to be segregated from those goods which are heavier in proportion to their size. The large goods may be stored toward the outer walls where the ceiling height is greater, whereas heavier goods may be stored in the overlapping portions.

What I claim as my invention is:

1. A structure for the purpose specified having a plurality of floors disposed at half-story intervals one above the other, and of less width than the overall width of the structure, the inner edge of each floor overlapping the inner edge of the floor next thereabove to provide storage space therebetween.

2. A structure for the purpose specified including enclosing walls and superposed stories extending from one wall towards the opposite wall but having its inner edge terminating short thereof, and half-stories at a

level intermediate said stories and having an overlapping edge terminating within the inner edge of the stories next thereabove, to provide storage space therebetween.

3. A structure for the purpose specified having a plurality of floors disposed at half-story intervals one above the other, and of less width than the overall width of the structure, the inner edge of each floor overlapping the inner edge of the floor next thereabove to provide storage space between them of restricted clearance, pairs of ramps affording communication between each story and the half-stories next thereabove and therebelow, the ramps in each pair departing from the inner line of the restricted clearance storage space of a given story and terminating at the inner line of the restricted clearance storage space on the half-stories next thereabove and therebelow, respectively.

4. A structure for the purpose specified including enclosing walls and superposed stories each extending from the front and rear walls towards the opposite wall, but terminating short thereof to form sections with their inner edges spaced, half-stories at levels intermediate said stories and positioned between the spaced inner edges thereof, four pairs of ramps, two pairs affording communication between said half story and the front section of each story next thereabove and therebelow, and the other two pairs affording communication between the half-story and the rear sections of corresponding stories, the front and rear sections of said stories being arranged to provide a lateral aisle communicating between the ramps leading up and down therefrom to adjacent half-stories, the half-story being arranged to provide two longitudinal aisles communicating between pairs of ramps leading to adjacent story sections at opposite ends but at like sides of the structure, and the half-story being likewise arranged to provide a lateral aisle affording communication between the two pairs of ramps leading from the half-story to the story sections at the same end of the structure.

Signed at Seattle, King County, Washington, this 25th day of August, 1924.

MOSE D. EAST.
